ATTORNEY.

UNITED STATES PATENT OFFICE.

SILAS BENT RUSSELL, OF ST. LOUIS, MISSOURI.

REINFORCING UNIT FOR CONCRETE.

951,150.

Specification of Letters Patent.

Patented Mar. 8, 1910.

Application filed February 1, 1909. Serial No. 475,449.

To all whom it may concern:

Be it known that I, SILAS BENT RUSSELL, residing in the city of St. Louis and State of Missouri, have invented a new and useful

5 Improvement in Reinforcing Units for Concrete, of which the following is a full, clear, and exact specification, reference being had to the accompanying drawings, which form a part thereof.

10 My invention relates to metal reinforcing used in connection with concrete for the purpose of stiffening and strengthening those parts of structures subjected to compressive and tensile stresses, and it belongs to that 15 type of reinforcing wherein the metal part of a beam or girder is made up as a unit in the shop and then put bodily in place on the structure where it is to be used, thus avoiding any chances of error in the construction 20 of the beam or girder due to carelessness or lack of skill on the part of the workman.

The object of my invention is to provide a means whereby the proper reinforcing for concrete beams, girders, columns, and similar 25 parts of structures made up in whole or in part of reinforced concrete may be made in the shop and then shipped and erected in place as a complete unit, and at the same time providing said unit with means whereby the 30 concrete is mechanically bonded to the reinforcing.

My invention is fully shown in the accompanying drawings where similar letters are used to designate similar parts.

35 Figure 1 is a view looking at the side of a unit; Fig. 2 is a view of a section along the line 1—1 of Fig. 1; and Fig. 3 is a view of a horizontal section along the line 2—2 of Fig. 2.

40 Referring to the figures, J is a web having attached thereto the flange I. At the edge of the web opposite the flange I, there is a head, G, shown as a bulb in Figs. 1 and 2. Projecting outwardly from, and preferably 45 at right angles with, the web J are barbs for the purposes of being embedded in the concrete and providing a mechanical bond between the unit and the concrete adjacent to it. In Figs. 1, 2, and 3 these barbs are 50 shown at C, D, E, and F, where they are made by punching holes through the web J and bending the pieces punched from the holes so that they will project outwardly from the web as indicated in the figures.

55 The barbs are preferably arranged at the top and bottom of the web and on both sides

thereof, so as to form a bond to hold the concrete in place on both sides of the web. The form of barbs shown in Figs. 1, 2, and 3 are provided with openings, P, adjacent 60 to the barbs through which the concrete passes and tends to strengthen the bonding between the unit and the concrete adjacent thereto. In the preferred form the barbs are arranged in two rows, one near the 65 top and the other near the bottom, along the web; and the barbs of each row are arranged to project alternately from opposite sides of the web; and the barbs are made flat and placed on the web so that when the unit is 70 used as a beam the flat sides of the barbs will be in vertical planes, thus making it easy to pack the concrete under and around them. The unit shown in Figs. 1, 2, and 3, is made of a special rolled form similar to the ordinary bulb beam of commerce. 75

When it is desired to use one of these units in a structure for the purpose of reinforcing a concrete girder or beam, the load to be carried thereby is determined and 80 then a rolled member of the proper length having a web with its accompanying flange and head piece of the proper size and thickness, is chosen and the barb members formed on the web at the shop; then the unit thus 85 formed is taken to the place where it is to be used and put in position where the reinforced concrete beam is to be. A suitable box or frame, such as is well known to those who do reinforced concrete work, is built 90 around the unit so as to have its internal dimensions those required for the reinforced concrete beam or girder; and then the concrete is poured into this box around the reinforcing unit and thoroughly tamped and 95 made to cover and engage with the barbs and to pass through the openings P adjacent thereto. The reinforcing unit is preferably put with the flange I at the bottom so that it will take up most of the tension 100 to which the reinforced concrete beam may be subjected and the head G is placed at the top. The head G is made smaller than the flange I, because the compression to which the reinforced concrete beam may be subjected will be almost wholly taken up by the concrete, while the tension being on the lower part of the beam will be taken up by the flange I. Shear and other vertical and diagonal stresses in the beam will be taken 105 up by the web of the unit. The barbs and the holes adjacent to them mechanically 110

bind the concrete to the reinforcing unit so that the two act together as one, thus increasing the strength of the reinforced concrete beam.

5 It is evident that this unit is adapted to be used not only in reinforced concrete subjected to both tension and compression, but also in columns and wherever it is necessary to have a reinforced concrete member that 10 is subjected to either tension or compression or both.

While the flange I is shown at the bottom of the web J and the part G is called a "head," it is evident that this is only done 15 for the purpose of illustration in the specific form shown in the drawings, and to turn the beam upside down so that the flange would be at the top and the head at the bottom, would make no material difference 20 as to the manner of action of the unit in a reinforced concrete structure.

The position, size and shape of the barbs on the web may be varied, and the size of the web and the shape and size of the flange 25 and head may be adapted to suit the requirements of different conditions.

What I claim as new and desire to secure by Letters Patent, is:

1. A reinforcing unit for concrete consisting of a web having flat barbs projecting outwardly therefrom, said barbs being arranged in two rows one near the top and one

near the bottom of the web and being formed of material punched out and bent back from the web so as to leave an opening adjacent to each barb and having their flat sides in planes substantially at right angles with the length of the unit, the barbs of each row being arranged so that they project alternately from opposite sides of the web, and a flange on one edge of the web, substantially as described.

2. A reinforcing unit for concrete consisting of a web having flat barbs projecting outwardly therefrom, said barbs being arranged in two rows one near the top and one near the bottom of the web and being formed of material punched out and bent back from the web so as to leave an opening adjacent to each barb and having their flat sides in planes substantially at right angles with the length of the unit, the barbs of each row being arranged so that they project alternately from opposite sides of the web, a flange on one edge of the web, and a head on the web opposite the flange, substantially as described.

In testimony whereof I have signed my name to this specification in the presence of two subscribing witnesses.

S. BENT RUSSELL.
